MAGNETOELECTRIC IGNITION APPARATUS

Wilhelm Walther, Stuttgart, Germany, assignor
to Robert Bosch Aktiengesellschaft, Stuttgart,
Germany

Application December 12, 1931, Serial No. 580,662
In Germany March 24, 1931

6 Claims. (Cl. 171—252)

The invention relates to a magneto electric ignition apparatus having a stationary magnet, a stationary armature, and a rotating member having conducting pieces or segments for the flux lines, in which the pole-shoes of the magnet are directed parallel to the axis of rotation of the conducting piece for the flux lines.

The invention has for its object an apparatus which can produce eight or more sparks per revolution. According to the invention, this is attained by employing in known manner a rotary member having conducting pieces or segments for the flux lines, with the rotary member having more than two segments, and by employing a suitable formation and distribution of the iron in armature and magnet whereby only two segments at a time form the path for the flux lines between the armature and the magnet.

An example of construction of the invention is shown in the drawing, in which:—

Figure 1 is a sectional view of a magneto.

Figure 2 a section on the line $x-y$ of Fig. 1.

In the drawing, a denotes the stationary magnet, which consists of several flat bar-magnets having in the centre an opening for the passage of the shaft b . The pole-shoes e of this magnet extend parallel to the shaft b over the rotating member c bearing the segments for the flux lines, which member is secured on the shaft b . A winding i is provided on the core k of the armature, which is also stationary, to which core the pole-shoes m of the armature are connected. The armature pole-shoes extend so far round the rotary member c that the terminal edges of the pole-shoes of the magnet and of the armature have a spacing about the circumference of said member which corresponds to this circumference divided by the number of cylinders of the engine with which the magneto is to be used.

The number of the segments q on the rotary member c for the lines of force is half as great as the number of cylinders of the engine. The segments on the circumference of the rotary member c are of such a length that they extend around the rotary member from the trailing edge of the one armature pole-shoe to the leading edge of the other succeeding armature pole-shoe in the direction of rotation.

It therefore follows that, with the pole shoes e of the magnet between the pole shoes m of the armature, when, in the rotation of the rotary member c , two opposite segments extend, as shown for the top and bottom segments q in Fig. 2, across the pole shoes e of the magnet and from the trailing edge of one armature pole

shoe to the leading edge of the other in the direction of rotation, there is a path for the magnetic lines of force, from one pole shoe of the magnet, say the upper one in Fig. 2, to the other or bottom pole shoe through the top and bottom segments q and those portions of the pole shoes m of the armature therebetween, and the armature will be short circuited.

It is also to be observed from Fig. 2, that the spacing apart of the segments q is less than the width, in the direction of rotation of the segments, of the pole shoes e of the magnet, so that at no time in the revolution of those segments will one pair of oppositely disposed segments fail to come into flux-distributing relation with the magnet pole shoes and the armature pole shoes.

As already stated, when two opposite segments come into the position shown for the upper and lower segments in Fig. 2, the lines of force extend directly from pole to pole of the magnet through those rotor segments and the adjacent portions of the pole shoes of the armature and the armature core is short-circuited. This occurs also at those points in the revolution of the segments disposing each of the magnet shoes e across the gap between two adjacent segments. During all other times in the revolution of the segments, each two oppositely disposed segments will come into positions successively bridging the gaps on the opposite sides of the magnet pole shoes between those shoes and the armature pole shoes in a manner to so direct the magnetic flux through the armature as to produce spark impulses double the number of the flux distributor segments; or, eight spark impulses for the four-segment arrangement shown in Fig. 2. This will more clearly appear by selecting two segments for consideration, those now appearing as the upper and lower segments in Fig. 2, and taking their revolution as clockwise. In their position as shown in Fig. 2, these segments short circuit the armature as already stated. But in their clockwise revolution, what is now top segment q moves to a position bridging the gap between upper magnet pole shoe e and right hand armature pole shoe m , and what is now bottom segment q moves to position bridging lower shoe e and left-hand shoe m , to provide a flux path from upper shoe e , upper segment q , right hand shoe m , armature core k , left hand shoe m and lower segment q to lower shoe e . Then when what is now the upper segment q , as the parts are viewed in Fig. 2, has

made nearly a complete revolution, it comes into 105 110

position bridging the gap between the shoe *e* and the left hand shoe *m*, and a flux path is established through the armature but in reverse direction to the first-mentioned path. So that 5 each of the four segments, in cooperation with its diametrically oppositely disposed segment, successively establishes and interrupts two oppositely directed flux paths or lines of force through the armature for each revolution of the segments; and, as already pointed out, when the 10 flux through the armature is interrupted there is still a flux path from pole to pole of the magnet. By this arrangement the magnetic flux in the magnet is never interrupted, and the magnet does not become weakened.

It is, of course, to be understood that the rotary member *c* is of non-magnetic material, and that the segments *q* are of material to conduct the magnetic flux so as to function as the flux distributor.

In the operation of the magneto always two segments *q* only are simultaneously traversed by the magnetic flux, whilst the other segments remain out of action.

25 The distribution of the iron in the pole-shoes of the armature and magnet about the periphery of the rotary member *c* may, of course, be exactly the reverse of that shown without affecting the mode of working of the magneto.

30 I declare that what I claim is:

1. An inductor magneto comprising, in combination, a stationary magnet, a stationary armature, a rotor having circumferentially spaced flux-conducting segments of substantially equal extent in the direction of rotation and disposed on said rotor in a plurality of pairs of diametrically opposed segments all lying in one plane transverse to the axis of said rotor, pole shoes on said magnet and on said armature extending 35 in said plane in such circumferentially spaced relation about said rotor as to cause each pair of segments in succession to bridge said pole shoes on said magnet and said armature while all the other segments are out of said bridging 40 relation with said pole shoes during each cycle of revolution of said segments.

2. An inductor magneto comprising, in combination, a stationary magnet, a stationary armature, a rotor, pole shoes extending from said 50 magnet and said armature about said rotor in alternation of magnet pole shoe and armature pole shoe and with said pole shoes evenly spaced circumferentially of said rotor and all lying in one plane transverse to the axis of said rotor, 55 and a plurality of pairs of diametrically opposed flux-conducting segments on said rotor of such extent and spacing circumferentially of said rotor in said one plane as to cause each pair of segments in succession to bridge said pole shoes of 60 said magnet and said armature while the other segments are out of said bridging relation during each cycle of revolution of said segments.

3. An inductor magneto comprising, in combination, a stationary magnet, a stationary armature having a winding energized by said magnet to produce sparking impulses, a rotor, pole shoes extending from said magnet and armature and a plurality of pairs of diametrically opposed flux-conducting segments on said rotor, with said 65 shoes so disposed in circumferentially spaced relation about said rotor and said segments spaced circumferentially on said rotor as to cause each

pair of segments in succession during each cycle of their revolution to so bridge said pole shoes of said magnet and said armature and so interrupt said bridge as to produce sparking impulses in said armature winding of double the number of said segments.

4. An inductor magneto comprising, in combination, a stationary magnet, a stationary armature, a rotor, two pole shoes extending from said armature to diametrically opposed positions about said rotor, two pole shoes extending from said magnet to diametrically opposed positions about said rotor between said armature pole shoes, the terminal edges of all said pole shoes being evenly spaced apart, and a plurality of pairs of diametrically opposed flux-conducting segments on said rotor, with each segment of an extent circumferentially of the rotor just equal to the distance circumferentially of the rotor between the adjacent terminal edges of the armature shoes on 90 opposite sides of the rotor, said magnet pole shoes and armature pole shoes and said segments all being disposed to lie in one plane transverse to the axis of said rotor, whereby during each cycle of rotation of the rotor the segments of each pair 95 in succession with the segments of the remaining pair or pairs attain positions so bridging the gaps between the magnet pole shoes and the armature pole shoes on opposite sides of the rotor as to direct the magnetic flux through the armature 100 in one direction, then to direct the magnetic flux from one magnet pole shoe directly to the other through terminal portions of the armature pole shoes in a manner to short circuit the armature and then to direct the magnetic flux through 105 the armature in a direction reverse to the first.

5. An inductor magneto comprising, in combination, a stationary magnet, a stationary armature, a rotor, two pole shoes extending from said armature to diametrically opposed positions about said rotor, two pole shoes extending from said magnet to diametrically opposed positions about said rotor between said armature pole shoes, all of said pole shoes lying in one plane transverse to the axis of said rotor and the terminal edges of 115 all said pole shoes being evenly spaced apart in said plane, and a plurality of pairs of diametrically opposed flux-conducting segments on said rotor, with each segment of an extent in said plane circumferentially of the rotor just equal to the distance circumferentially of the rotor between the adjacent terminal edges of the armature shoes on opposite sides of the rotor and with the segments spaced apart a less distance than the width of the magnet pole shoes measured circumferentially of the rotor, whereby at all times during 120 each cycle of rotation of the rotor the segments of one or more pairs are in positions so bridging the gaps between the magnet pole shoes and the armature pole shoes as to maintain an uninterrupted path for the magnetic flux from pole to pole of the magnet while the pairs of segments 125 function successively to establish and interrupt the flux through the armature.

6. An inductor magneto as defined in claim 3 130 and further characterized by a disposal of said magnet pole shoes, said armature pole shoes and said flux-conducting segments in positions circumferentially of said rotor all lying in one plane transverse to the axis of said rotor.
